UNITED STATES PATENT OFFICE

2,366,928

PENCIL SHARPENER

Anthon H. Paschell, Des Moines, Iowa

Application January 7, 1944, Serial No. 517,312

3 Claims. (Cl. 120—87)

The present invention relates to sharpening devices and more particularly to lead pencil sharpeners.

It is an object of the invention to provide a lead pencil sharpener device, the parts of which are so constructed and cooperatively arranged that they may be readily secured to or removed from an end of a lead pencil for protecting against breakage of a sharpened point of the pencil at times when the sharpener and pencil are not in use, said device further being constructed so that the pencil is accurately centered axially of the device during a sharpening of the writing lead of the pencil.

Another object of the invention is to provide a device for said purposes, the parts of which are so constructed and arranged that said parts, together with the lead pencil, may be secured together at times when said device and pencil are secured to the clothing of the user when not in use for preventing loss of the pencil and said device.

A further object of the invention is to provide a device having a cutter which may be readily removed for a replacement or sharpening of the blade thereof.

Other and further objects and advantages of the invention will be obvious from the following detailed description thereof.

In the drawing:

Figure 1 is a side elevation of the new device and showing a fragment of a lead pencil attached thereto for storing the pointed end of a pencil within the new device.

Figure 2 is a plan view showing the point of the pencil in a writing or reverse position with respect to the showing thereof in Figure 1.

Figure 3 is a transverse section taken approximately on line 3—3 of Figure 5.

Figure 4 is a longitudinal section of the new device, a resilient clip employed being omitted.

Figure 5 is a view similar to Figure 1 and showing the new device turned at an angle of approximately 180 degrees with respect to the showing thereof in Figure 1.

Figure 6 is a perspective view of a cutter or blade employed.

In the drawing, a conventional lead pencil is generally indicated at 10 having a stick of lead graphite axially disposed with respect to and within the casing of the pencil. The lead is provided with a sharp writing point 11 at the end of the wooden reinforcing casing 12 thereof. As is well known, the graphite lead is fragile, easily broken, and becomes worn away through use.

The new device includes an elongated cylindrical sleeve 13, having an open end 14 and a closed end 15, the interior of the latter being of conical shape in longitudinal section and of circular shape in cross section, as shown in Figure 4. Each end of the sleeve is preferably provided with an annular reinforcing ferrule 16, whereby the sleeve 13 may be of light weight material.

The sleeve may be moulded of any one of several suitable plastic materials, and as best shown in Figure 4, the end of the wall of the conical portion 15 at the apex of said conical wall, is provided with an opening 17 in communication with a bore 18, whereby at times when the pencil is inserted into the conical portion 15, the pointed end 11 of the pencil is received in the bore 18 for protecting said pointed end against breakage at times when the pencil is stored and not in use.

An end of the sleeve adjacent the bore 18 is preferably provided with a recess 19 for snugly receiving therein a member 20 formed of rubber, said member being suitable for mark erasing purposes.

The wall of the conical portion of the sleeve 13 is provided with an opening 21 across which a cutter 22 is disposed. The sleeve 13 is further provided with an outwardly disposed lug 23 having a flange 24 against which one end of the cutter 22 is disposed in use. Adjacent the bore 18, the sleeve is provided with a kerf 25 for receiving therein the other end of the cutter.

As best shown in Figure 3, a detent or screw 26 is disposed through the aperture 27 of the cutter 22, said screw being threadedly engaged in the lug 23 for preventing movement of the cutter transversely with respect to the sleeve, said flange 24 and kerf 25 preventing swinging movements of the cutter to an undesired extent.

As thus described, it will be noted that the sharp elongated cutting edge 21a of the cutter 22 is normally held at an angle complementary to the conical shape of the portion 15 of the sleeve for pencil sharpening purposes.

In order to sharpen the lead pencil, the pointed end of the latter is inserted into the sleeve, the new device being held in the fingers of one hand of an operator while the latter rotates the pencil with his other hand, pressing the pencil toward the rubber 20, whereby shavings from the pencil 50 pass outwardly through the opening 21.

The new device further includes an elongated resilient clip 28, having an end 29 which is rigidly secured to the sleeve by any suitable means. If desired, the clip 28 may be formed integral with 55 the sleeve as shown in Figure 1.

As best shown in Figure 5, the clip is of arcuate shape in side elevation, preferably being provided with a ball 30 at the free end thereof, said arcuate shape providing a space 31 between the clip and the pencil at times when the latter is inserted into the sleeve.

As thus described, it will be noted that the free end of the resilient clip 28 is urged by the inherent resiliency thereof against the lead pencil for cooperatively locking the writing point end of the lead pencil into the holder or sharpening device for protecting the writing point of the pencil.

At times when the pencil and new device are to be transported about the person of a user, the pencil and new device are joined together by means of the clip 28, as shown in Figures 1 and 5, and the end of the lead pencil, which includes the rubber 20, is inserted into a vest pocket of the user in a manner whereby the cloth adjacent the edge of said pocket extends into the space 31, the ball 30 of the clip at this time being urged toward and against the inner surface of the cloth of the pocket, and pressing the outer surface of the cloth against the lead pencil in a manner whereby the writing point of the pencil is not only protectingly locked to the new sharpening device, but is also cooperatively locked to the clothing of the user for preventing loss of the pencil and the new device during transportation of said items and at times when said items are not in use.

From the foregoing description, it is thought to be obvious that a pencil sharpener and holder

constructed in accordance with my invention is particularly well adapted for use by reason of the convenience and facility with which it may be assembled and operated, and it will also be obvious that my invention is susceptible of some change and modification without departing from the principles and spirit thereof and for this reason, I do not wish it to be understood as limiting myself to the precise arrangement and formation of the several parts herein shown in carrying out my invention in practice, except as claimed.

I claim:

1. A device for the purpose described comprising a molded plastic sleeve having an open end and a closed end, a slot disposed longitudinally through a side wall of said sleeve, said sleeve having flanged portions adjacent said slot ends, a cutter seated in said flanged portions, and means removably securing said cutter to said sleeve.

2. A device as claimed in claim 1 in which the closed end of the sleeve is provided with a bore.

3. In a device of the character described a non-metallic member having a recess of conical shape at one end thereof, a slot disposed longitudinally through a side wall of said member, a lug adjacent one end of said slot, a flange on said lug, a kerf at the other end of said slot, a cutter extending into said recess through said slot, said cutter having one of its ends seated beneath said flange and its other end in said kerf, and fastening means removably securing said cutter to said lug.

ANTHON H. PASCHELL.
